MEANS FOR DETACHABLY CONNECTING
BRACED SUPPORTING LEGS TO GUN
MOUNTINGSHeinrich Herlach and Fritz Herlach, Solothurn,
Switzerland, assignors to Waffenfabrik Solo-
thurn A.-G., Solothurn, Switzerland, a cor-
poration of SwitzerlandApplication November 27, 1933, Serial No. 699,997
In Germany December 19, 1932

6 Claims. (Cl. 89—40)

This invention relates to gun mountings supported by braced legs which can be collapsed and removed if desired, for convenience of transport.

In such mountings which are adapted to travel on wheels, it is customary—when the travelling position is assumed—for a supporting leg to be released from its connection with the gun mounting and then, with the two other legs which are placed together, used for forming a trail. Also tripod carriages, which are transported divided up into separate loads, necessitate for transport the removal of at least one supporting leg, which, when the gun mounting is assembled for firing, must be specially reattached.

In a certain kind of gun mounting intended and suitable for machine guns of the heavier type, of the order of magnitude of 2 cm. bore or more, for each supporting leg there are provided two different connections which, when the leg is removed from or connected to the body of the gun carriage, must both be attended to at the same time. One of these serves for fixing the end of the supporting leg on the body of the gun carriage and the other belongs to a removable bracing member engaging with the supporting leg and adapted to be removed therewith. The object of the invention is, in the case of such arrangements with a plurality of points of connection, to make the operation of detaching and reassembling a supporting leg so simple and safe that it can be completely mastered by the gun crew, with a minimum of successive manipulations and can also be carried out rapidly and without mistakes in exceptional circumstances where great speed is essential, and at times when momentary confusion prevails.

With this object in view, according to the invention, in the case of braced supporting legs, a locking device for fastening the end of the supporting leg to the body of the gun mounting, is brought into operative connection with the bracing strut, so that the closing or opening of the supporting leg connection is effected by the movement of the legs into and out of bracing position.

The drawing shows a particularly advantageous example of construction giving details of the invention.

Fig. 1 is a side view of a tripod gun mounting with a removable front leg; Figs. 2 and 3 show the supporting leg by itself, removed for transport.

For the attachment of the supporting leg 1 to the body 2 of the gun mounting, there are provided two bearing points disposed one over the

other. The end of the supporting leg is hitched on a pin 3 on a lower lug 4. A flattened bolt 6 mounted in an upper lug 5 and which is adapted to be fixed in two different pivotal positions, receives the hook-shaped end 7 of a bracing strut 8 which is connected to the supporting leg 1 so as to pivot about the pin 9. In the position shown in Fig. 1, the bolt 6 couples the hitched strut 6 with the body 2 of the gun mounting, while after moving through about 90°, the strut may be released for folding down against the leg.

The means of connection of the supporting leg 1 consist of two hook-shaped rigid bearing jaws 10 which are adapted to engage the supporting pin 3 on the body of the gun mounting and are supplemented by the movable jaw 11 so as in effect to form a pair of tongs. The jaw 11 is a sliding member and is held in the closed or locking position by a spring 12. The supporting leg connected as shown in Fig. 1 is coupled with the body 2 of the gun mounting, rigidly and in fixed direction, at the three points 3, 6 and 9, but for the purpose of levelling and changing the height of fire, the gun carriage can be adjusted by the length of the bracing strut 8 being changed.

Now if for the removal of the supporting leg 1, the strut 8, after releasing its connection 6—7, be folded about the bolt 9 down against the leg, on the last part of the swinging movement a projection 13 on the strut presses on a shoulder on the sliding member 14 guided in the head of the supporting leg. This sliding rocks a lever 15 which engages therewith and also with the movable jaw 11, whereby the jaw 11 is retracted from its closed position and into the end of the supporting leg (Fig. 2). The hitherto closed bearing tongs 10, 11 are now opened and the leg 1, by the disengagement of its hook 10 from the bolt 3, can easily be removed from the gun mounting. The strut 8 is secured in its collapsed position by a spring clamp 16 on the supporting leg, and the clamping power of the said spring clamp suffices to withstand the jolting which occurs during transport and also the opposing action of the spring 12.

The above described manipulation which can be carried out easily and quickly on the removal of the connected supporting leg from the gun mounting is, therefore, as follows: The retaining bolt 6 for the strut 8 is turned round, the strut is collapsed and the supporting leg 1 is disconnected. In connecting the leg, these operations are carried out in reversed order.

We claim:—

1. A gun carriage comprising a gun mounting, removable legs adapted to support the mounting, joints with release mechanism connecting the legs to the mounting, struts movable into and out of effective position for bracing the legs relatively to the gun mounting, and means actuated automatically by the said movements of the struts for engaging and releasing the leg joints.
- 10 2. A gun carriage comprising a gun mounting, removable legs adapted to support the mounting, joints with release mechanism connecting the legs to the mounting, struts for bracing the legs relatively to the mounting and removably connected thereto, each strut when disconnected being pivotable into a position alongside the leg, and means actuated automatically by the struts for engaging and releasing the leg joints.
- 15 3. A gun carriage comprising a gun mounting, removable legs adapted to support the mounting, joints with release mechanism connecting the legs to the mounting, struts for bracing the legs relatively to the mounting and removably connected thereto, each strut when disconnected being pivotable into a position alongside the leg, and means actuated automatically by the struts for engaging and releasing the leg joints, and retaining means on the legs for holding the struts in non-bracing position.
- 20 4. A gun carriage comprising a gun mounting,

30

joint pins on said mounting, legs adapted to support said mounting, jaw members on said legs for engaging the joint pins, one of said members on each leg being retractable to permit the leg to be removed from its joint pin, struts movable into and out of effective position for bracing the legs relatively to the gun mounting, and means on the struts for actuating the retractable jaw members.

5

5. A gun carriage comprising a gun mounting, joint pins on said mounting, legs adapted to support said mounting, jaw members on said legs for engaging the joint pins, one of said members on each leg being retractable to permit the leg to be removed from its joint pin, struts movable into and out of effective position for bracing the legs relatively to the gun mounting, springs urging the movable jaws towards the joint pins, and means on the struts for retracting said jaws against the action of their springs when the struts are pivoted into non-bracing position.

10

6. A gun carriage according to claim 1 in which means are provided for removably connecting the struts to the mounting, said means comprising flattened joint pins, hooks on the struts embracing said joint pins, and means for turning the joint pins to enable their flat portions to enter and leave the hooks.
